PHOTOGRAPHIC CAMERA

Ohiko Yagi, 3-6 Naka-Magome, 1-chome,
Tokyo, Japan

Filed Mar. 13, 1968, Ser. No. 10,952

Claims priority, application Japan Sept. 18, 1967

Term of patent 7 years

(Cl. D61—1)

FIG. 1

FIG. 2

FIG. 3

FIG. 4

FIG. 5

FIG. 6

FIGURE 1 is a front view of a photographic camera, showing my new design;

FIGURE 2 is a rear view;

FIGURE 3 is a left side view;

FIGURE 4 is a right side view;

FIGURE 5 is a plan view; and

FIGURE 6 is a bottom view.

Portions of FIGURES 1, 2 and 4 are diagonally lined to indicate transparency.

I claim:

The ornamental design for a photographic camera, substantially as shown and described.
